US00D979778S

(12) **United States Design Patent** (10) **Patent No.:** **US D979,778 S**
(45) **Date of Patent:** **** Feb. 28, 2023**

(54) **HEATING PAD FOR FOOT**

(71) Applicant: **Kobayashi Pharmaceutical Co., Ltd.**,
Osaka (JP)

(72) Inventors: **Kota Nakabayashi**, Osaka (JP);
Tetsuya Maruyama, Osaka (JP)

(73) Assignee: **Kobayashi Pharmaceutical Co., Ltd.**,
Osaka (JP)

(**) Term: **15 Years**

(21) Appl. No.: **29/796,286**

(22) Filed: **Jun. 23, 2021**

(30) **Foreign Application Priority Data**

Dec. 25, 2020 (JP) ..... 2020-028193 D
